(57) **CLAIM**

The ornamental design for a terminal block portion of a battery pack, as shown and described.

DESCRIPTION

FIG. 1 is a rear perspective view of a terminal block portion of a battery pack, such as a battery pack for a power tool, an outdoor tool or other battery-powered device.

FIG. 2 is a front perspective view of the portion of the battery pack shown in FIG. 1.

FIG. 3 is a rear view of the portion of the battery pack shown in FIG. 1.

FIG. 4 is one side view of the portion of the battery pack shown in FIG. 1.

FIG. 5 is another side view of the portion of the battery pack shown in FIG. 1; and,

FIG. 6 is a top view of the portion of the battery pack shown in FIG. 1.

The broken lines immediately adjacent the shaded areas represent the bounds of the claimed design while all other broken lines are directed to environment and are for illustrative purposes only; the broken lines form no part of the claimed design.
